(57) **CLAIM**

The ornamental design for a two-legged cube connector for wall panel system, as shown and described.

DESCRIPTION

FIG. 1 is a top perspective view of a two-legged cube connector for wall panel system showing our new design.

FIG. 2 is a bottom perspective view thereof.

FIG. 3 is a front elevation view thereof.

FIG. 4 is a rear elevation view thereof.

FIG. 5 is a top plan view thereof.

FIG. 6 is a bottom plan view thereof.

FIG. 7 is a left side elevation view thereof; and,

FIG. 8 is a right side elevation view thereof.

1 Claim, 6 Drawing Sheets
